HAT BRIM IRONING MACHINE

Rudolph G. Segschneider, Yonkers, N. Y.

Application April 16, 1935, Serial No. 16,544

17 Claims. (Cl. 223—21)

The general object of the present invention is to provide an improved machine for ironing the brims of hats. More specific objects of the invention are to provide a hat brim ironing machine which is simple in construction and operation, relatively inexpensive to construct and maintain, and capable of excellent operative results; and in which, during the ironing operation, the hat being ironed may have its crown supported by a crown block of standard form used in hat factories for other purposes, and which is adapted for use without modification or special adjustments in ironing hats of different sizes, shapes and weights. A further and important specific object of the invention is to provide a machine for the purpose stated, which is substantially free from the tendency to rim buckling and wrinkling experienced in the use of prior hat brim ironing machines, particularly in ironing hats having thin, or light weight, soft brims.

The various features of novelty which characterize my invention are pointed out with particularity in the claims annexed to and forming a part of this specification. For a better understanding of the invention, however, and the advantages possessed by it, reference should be had to the accompanying drawing and descriptive matter in which I have illustrated and described a preferred embodiment of the invention.

30 Of the drawing:

Fig. 1 is a plan view of a hat brim ironing machine;

Fig. 2 is an elevation of the machine shown in Fig. 1, with the lower portions of the machine frame work broken away; and

Fig. 3 is a section on the line 3—3 of Fig. 1, with the supporting framework of the machine removed.

In the embodiment of the invention shown in the drawing, the supporting frame work of a machine comprises corner posts A, on which is mounted a stationary table B of rectangular outline. The table B is formed with an opening B' to receive parts including portions located above and below the table, and is formed at its upper side with uprising projections or lugs B², B³, and B⁴, on which other parts are mounted as herein-after described. The crown of a hat C having its brim ironed, is supported during the ironing operation on a crown block CC which may be of any usual form and type, provided only that it is formed with a central passage or socket CC', as is customary with ordinary crown blocks, so that it may loosely receive the hereinafter mentioned 55 guide pin M².

In the ironing operation, the hat brim C' which is being ironed, extends between, and is acted upon by upper and lower revolving irons D and E. The irons D and E have flat circular brim engaging surfaces, and are mounted on and revolved by vertical shafts D' and E' respectively, which are horizontally displaced from one another. Normally, and as shown, the peripheral edge of the iron D extends into contact with the crown of the hat at the bottom hat band line or corner at which the upper surface of the brim merges into the outer surface of the crown. The diameter of the iron D is preferably a little less than double the average brim width of hats worked upon, so that the major portion of the lower face of the iron D in engagement with the brim at any time will lie between the axis of the shaft D' and the crown of the hat. The upper ironing face of the lower iron E which supports and works on the under side of the brim C', is substantially larger in diameter than the ironing face of the upper iron D, and the axes of the shafts D' and E' are preferably displaced as shown, by a distance a little greater than half the diameter of the iron D, so that the axis of the iron E intersects the crown of the hat adjacent the portion of the latter nearest to the shaft D'.

The shaft D' is journalled, and mounted for longitudinal movement, in upper and lower bearings D² and D³ carried by U shaped bracket parts G' carried by, and advantageously cast integrally with a vertical frame member G. The latter extends through the opening B' in the table B, and is provided with one or more lateral bracket 30 or flange portions G², two being shown, which are bolted against the upper side of the table B, the connection between each extension G² and the adjacent vertical portion of the frame member G being stiffened by an integral fillet G₃. The bearings D² and D³ include flanges bolted to the brackets G', removable shims D⁴ being provided to secure proper shaft and bearing alignment.

In operation, the iron D is held in engagement with the upper side of the hat brim C' with suitable pressure, by a compression spring D⁵ surrounding the shaft D' and acting between the upper bearing D² and a collar D⁶ rigidly fastened on the shaft D' adjacent but above the lower bearing D³. The shaft D' may be raised to permit a hat brim to be inserted between or removed from the irons by a lever F acting on the collar D⁶. The lever F is pivotally connected at one end to one leg of the U shaped bracket G' by a pivot pin F', and may be turned about the pivot pin 55

to engage with the under cut edge D⁷ of the collar D⁶ and raise the latter by a wedging action. To facilitate its turning movement, the lever F is provided at its free end with an uprising handle F².

The lower iron shaft E' is journalled in upper and lower bearings E² and E³, respectively supported by upper and lower brackets E⁴ which are bolted to portions of the frame G beneath the table B. A collar E⁵ rigidly secured to the shaft E' engages the upper side of the lower bearing E³ and provides a thrust bearing holding the iron E at the proper elevation.

The shafts D' and E' are both rotated by a vertical drive shaft J which extends through the table B. A pulley J' carried by the shaft J at its upper end, is connected by a belt DJ to a pulley D⁸ secured to the upper end of the shaft D'. At its lower end the shaft J carries a pulley J² which is connected by a belt EJ to a pulley E⁶ secured to the lower end of the shaft E'.

As indicated in the drawing, the two belt rims or portions extending between the pulleys over which the belt passes, are crossed in the case of the belt EJ, but not in the case of the belt DJ, so that the shaft D' rotates in the same direction as the shaft J, while the shaft E' rotates in the opposite direction. As seen in Fig. 1, the shaft D' and iron D rotate in the clockwise direction, while the shaft E' and iron E rotate in the counter-clockwise direction. The pulleys J', J², D⁸, and E⁶, are so relatively proportioned that the shaft D' has a lower speed of rotation than shaft E', and with the proportions shown, the rotative speed of the shaft D' is half that of the shaft E', and may be of the order of 16 revolutions per minute. The irons D and E are heated by gas burners I and H, respectively, above and below the table B. As shown, the burner pipe I rests in 40 and is partially supported by the table projection B⁵.

As shown, the shaft J carries a worm gear J³ which is rotated by a worm L' carried by a horizontal shaft L forming the main power shaft of the machine and journalled in bearings L² adjustably secured to the table B. The shaft L carries a driving pulley L³ at one end. The shaft J passes through and has a bearing in the table B⁵ and is also journalled in upper and lower bearings J⁶ and J⁷ supported by upper and lower U shaped brackets J⁶ and J⁷, respectively, which are detachably secured to the frame member G.

In operation the crown block CC is yieldingly urged with the desired force toward the iron D by a spring K anchored at one end to the framework A and connected at its other end to one end of a flexible element K'. The latter runs over a pulley K² mounted on the table B, at the under side of the latter, and has its second end connected to a down turned outer end portion M' of a hat guide member M. The latter, as shown, comprises a horizontal body portion in the form of a flat bar which extends in a direction generally radial to the shafts D' and E', and carries at its end adjacent those shafts, the previously mentioned uprising stud M² loosely received in the central socket CC' of the crown block CC. The member M is permitted guided movements in the general direction of its length by guide pins or studs M³ and M⁴ located at greater and lesser distances, respectively, from the shafts D' and E', and passing through slots M⁵ and M⁶, respectively, formed in the member M. As shown, the pins or studs M³ and M⁴ are formed with screw heads at their upper ends and have lower

threaded portions screwed into the projections B² and B³ respectively, on which the member M is supported and moves. The member M is provided at its outer end with an uprising handle M⁷ for use in moving the member away from the irons D and E, in withdrawing a hat from the machine. As shown, the member M may be latched in its retracted position, by turning the member, when retracted, about the guide stud M⁴ sufficiently to cause the guide stud M³ to be received in a lateral extension M⁸ of the guide slot M⁵.

Advantageously, and as shown, the crown block and the hat are held out of engagement with the pin guide member M³ and the edges of the slot 15 M⁶ by a bridge member M⁹ of inverted trough form secured to the upper side of the member M, and having a smooth rounded upper side which forms a crown block support extending radially away from the crown block guide pin M². The 20 bridge member M⁹ holds the side of the crown block remote from the shafts D' and E' at a slightly higher elevation than the side of the crown block adjacent those shafts. This tilting of the crown block and hat is desirable as it facilitates the sharp definition of the hat corner at which the upper surface of the brim merges into the outer surface of the hat at the lower band line by the iron D which preferably is beveled off at the upper side, as indicated at D⁸, to assist in such 30 sharp corner definition. The spring K should be of sufficient length so that its tension will not vary much in normal operation as a result of the movement of the crown block guide toward and away from the shafts D' and E' as is necessary to 35 hold the hat crown against the periphery of the iron D continuously, notwithstanding the usual oval form of the crown block shown in Fig. 1.

The upper side of the hat brim C' is guided and caused to feed smoothly between the upper and lower irons D and E, by a plate-like guide member N adjustably mounted on the bracket or projection B⁴, and extending over the portion of the hat brim about to pass into engagement with the arm D. The edge of the guide N remote from the iron D is preferably rounded, or flared as shown, so that even though the hat brim is initially so shaped or distorted that portions of the brim extend upward considerably above the ironing face of the iron E, the guide N will smooth out the 50 brim and cause it to feed smoothly between the irons D and E.

In operation, with the iron D rotating in the clockwise direction and the iron E rotating in the counterclockwise direction, as seen in Fig. 1, the 55 hat and crown block will rotate about the crown block guide pin M² in the counter-clockwise direction. As previously explained, the hat corner at which the brim merges into the crown, is sharply defined by the peripheral edge of the 60 iron D, which exerts a direct rotating or feeding effect on the hat crown and crown block. The displacement of the iron shafts D and E from one another, and the differences in their rotative speeds each contribute to a movement of the brim 65 engaging surface of each iron relative to that of the other, and to the portion of the hat brim between the two irons, insuring a very effective ironing action on each side of the brim. The extended plane ironing surfaces in contact with 70 the brim and the compression of the latter between the irons under the yielding force tending to move the iron D toward the iron E, practically precludes any tendency to the wrinkling of the brim, even though the latter be very thin and 75

flexible, provided the brim is properly fed into engagement with the irons. Such feeding is insured by the action of the brim guide N when properly adjusted.

5 With my improved machine, the ironing operation on an individual hat ordinarily requires but a small fraction of a minute, but if the ironing operation is continued beyond the minimum time required for its completion, the hat will not be 10 injured thereby. In consequence, a group of my improved machines may advantageously be operated well by a single operator, who removes an ironed hat and inserts a hat to be ironed in each machine of the group one after another, so that 15 each machine of the group is continuously engaged in brim ironing operation, except during the brief intervals required for the removal of an ironed hat and the insertion of one to be ironed. It will be apparent that no adjustment in my 20 ironing machine is required ordinarily to permit its use in ironing the brims of hats varying markedly in size, shape, brim thickness or brim width.

Having now described my invention, what I 25 claim as new and desire to secure by Letters Patent, is:

1. In a hat brim ironing machine, the combination of two irons mounted for rotation about parallel axes laterally displaced from one another 30 and having parallel overlapping ironing faces transverse to said axes and respectively adapted to engage the upper and lower sides of an interposed hat brim.

2. In a hat brim ironing machine, the combination of two irons mounted for rotation about parallel axes laterally displaced from one another and having parallel overlapping ironing faces 40 transverse to said axes and respectively adapted to engage the upper and lower sides of the interposed brim of a hat, the iron engaging the upper side of said brim being circular and having a peripheral edge portion adapted to engage the crown of said hat.

3. In a hat brim ironing machine, the combination with two irons mounted for rotation about parallel axes laterally displaced from one another and having parallel overlapping ironing faces 50 transverse to said axes and respectively adapted to engage the upper and lower sides of the interposed brim of a hat, of means for supporting said hat for rotation about an axis generally parallel to and displaced from the axis of the iron engaging the upper side of the hat brim in the general direction of the displacement therefrom of the 55 axis of the other iron.

4. In a hat brim ironing machine, the combination with two irons mounted for rotation about parallel axes laterally displaced from one another and having parallel overlapping ironing faces 60 transverse to said axes and respectively adapted to engage the upper and lower sides of the interposed brim of a hat, of means for supporting said hat for rotation about an axis generally parallel to and displaced from the axis of the iron 65 engaging the upper side of the hat brim in the general direction of the displacement therefrom of the axis of the other iron, said means being movable in said general direction relative to the axes of said irons.

70 5. In a hat brim ironing machine, the combination with two irons mounted for rotation about parallel axes laterally displaced from one another and having parallel overlapping ironing faces 75 transverse to said axes and respectively adapted to engage the upper and lower sides of the inter-

posed brim of a hat, of means for supporting said hat for rotation about an axis generally parallel to and displaced from the axis of the iron engaging the upper side of the hat brim in the general direction of the displacement therefrom of the axis of the other iron, said means being movable in said general direction relative to the axes of said irons, and means for releasably holding the last mentioned means in a position in which the brim of a hat supported thereby does not extend into engagement with the iron adapted to engage its upper side. 5

6. In a hat brim ironing machine, the combination with two irons mounted for rotation about parallel axes laterally displaced from one another 15 and having overlapping ironing faces transverse to said axes and respectively adapted to engage the upper and lower sides of an interposed hat brim, said irons being relatively movable to vary the distance between their ironing faces, and 20 yielding means tending to move said irons toward one another to effect their simultaneous operative engagement with an interposed hat brim.

7. In a hat brim ironing machine, the combination of two irons mounted for rotation about parallel axes laterally displaced from one another and having parallel overlapping ironing faces 25 transverse to said axes and respectively adapted to engage upper and lower sides of an interposed hat brim with the iron engaging the underside of the brim extending beneath the crown of the hat, the iron engaging the upper side of the brim having a peripheral edge extending circularly about the axis of the iron, and adapted to engage the crown of said hat. 35

8. In a hat brim ironing machine, the combination with two irons mounted for rotation about axes laterally displaced from one another and each having an ironing face transverse to its axis of rotation and parallel to, and overlapping the ironing face of the other, said faces being respectively adapted to engage the upper and lower sides of an interposed hat brim, and means for rotating the two irons in respectively opposite 45 directions.

9. In a hat brim ironing machine, the combination with two irons mounted for rotation about axes laterally displaced from one another and each having an ironing face transverse to its axis of rotation and parallel to, and overlapping the ironing face of the other, said faces being respectively adapted to engage the upper and lower sides of an interposed hat brim, and means for rotating the two irons in respectively opposite 50 directions and with different angular velocities. 55

10. In a hat brim ironing machine, the combination with two irons mounted for rotation about axes laterally displaced from one another and each having an ironing face transverse to its axis of rotation and parallel to, and overlapping the ironing face of the other, said faces being respectively adapted to operatively engage the upper and lower sides of the interposed brim of a hat, the ironing face engaging the under side of the brim extending beneath the crown of the hat, 65 means above the last mentioned face, and laterally displaced from the other ironing face for revolvably supporting the crown of a hat having its brim interposed between said faces, and guiding means displaced from the last mentioned iron 70 and above the ironing face engaging the lower side of the brim and cooperating with the last mentioned face to guide the brim into operative engagement with the two ironing faces.

11. In a hat brim ironing machine, the com- 75

bination of two irons mounted for rotation about axes laterally displaced from one another, and having parallel overlapping ironing faces transverse to said axes and respectively adapted to engage the upper and lower sides of an interposed hat brim, said axes being displaced from one another by a distance exceeding the radius of the ironing face engaging the upper side of the brim, and means for rotating said irons each in a direction opposite to the direction of rotation of the other.

- 5 12. In a hat brim ironing machine, the combination of two irons mounted for rotation about axes laterally displaced from one another, and having parallel overlapping ironing faces transverse to said axes and respectively adapted to engage the upper and lower sides of an interposed hat brim, said axes being displaced from one another by a distance exceeding the radius of the ironing face engaging the upper side of the brim, and means for rotating said irons each in a direction opposite to the direction of rotation of the other, and a hat crown support revoluble about an axis displaced from the axis of the iron 10 20 25 engaging the upper side of the brim in the general direction of the displacement thereupon of the axis of the iron engaging the under side of the brim.

13. In a hat brim ironing machine, the combination with an iron revolving about an axis and having an ironing face transverse to said axis and adapted to engage the underside of the hat brim, a second iron having a circular ironing face parallel to the first mentioned face, and a crown engaging edge at the periphery of its face and revolving about the axis of its face, the last mentioned axis being parallel to and so laterally displaced from the first mentioned axis, that said edge is between said axes, and means for supporting a hat for revolution about an axis approximately parallel to the iron axes and displaced from said second mentioned axis, in the general direction in which the first mentioned axis is displaced therefrom, whereby said edge may engage the crown of a hat having its brim interposed between said irons.

14. In a hat brim ironing machine, the combination with an iron revolving about an axis and having an ironing face transverse to said axis and adapted to engage the underside of the hat brim, a second iron having a circular ironing face parallel to the first mentioned face, and a crown engaging edge at the periphery of its face and revolving about the axis of its face, the last mentioned axis being parallel to and so laterally displaced from the first mentioned axis, that said edge is between said axes, means for supporting a hat for revolution about an axis approximately parallel to the iron axes and displaced from said second mentioned axis, in the general direction in which the first mentioned axis is displaced therefrom, whereby said edge may engage the crown of a hat having its brim interposed be-

tween said irons, and means for revolving said irons in opposite directions.

15. In a hat brim ironing machine, the combination of a vertical shaft, an iron secured to the upper end of said shaft and having a horizontal upper ironing face, a cooperating iron, a second vertical shaft to the lower end of which is secured a second iron, the latter having a horizontal lower ironing face above the first mentioned ironing face, said shafts being horizontally displaced so that said ironing faces have overlapping portions adapted to operate simultaneously on the upper and lower sides of an interposed hat brim, a vertical driving shaft, and driving connections through which the last mentioned shaft 10 15 rotates the two shafts first mentioned in opposite directions.

16. In a hat brim ironing machine, the combination of a vertical shaft, an iron secured to the upper end of said shaft and having a horizontal upper ironing face, a second vertical shaft to the lower end of which is secured a second iron, the latter having a horizontal lower ironing face above the first mentioned ironing face, said shafts being horizontally displaced so that said irons 20 25 have overlapping portions adapted to operate simultaneously on the upper and lower sides of an interposed hat brim, means for rotating the last mentioned shafts in opposite directions, a supporting frame work comprising a table, a vertical 30 supporting member extending through said table, bearings for the first mentioned shaft carried by said supporting member beneath said table, bearings for the second mentioned shaft carried by said supporting member above the table, and a 35 crown block supporting member provided with an uprising support adapted to enter a crown block socket, said support being mounted on said table for movement relative thereto toward and away from the overlapping portions of said ironing 40 faces.

17. In a hat brim ironing machine, the combination of a vertical shaft, an iron secured to the upper end of said shaft and having a horizontal upper ironing face, a second vertical shaft to the 45 lower end of which is secured a second iron, the latter having a horizontal lower ironing face above the first mentioned ironing face, said shafts being horizontally displaced so that said irons have overlapping portions adapted to operate simultaneously on the upper and lower sides of an interposed hat brim, means for rotating the two shafts in opposite directions, a supporting frame work for said shafts comprising a table, a crown 50 block supporting member provided with an uprising support adapted to enter a central socket in a crown block, and a guide mounted on said table and laterally displaced from the second mentioned iron and extending above the first mentioned ironing face and cooperating with the 55 latter to guide the brim of a hat supported on said crown block into operative engagement with the overlapping portions of the two ironing faces.

RUDOLPH G. SEGSCHNEIDER.
